UNITED STATES PATENT OFFICE.

KARL SCHLÜTER, OF KIEL-GAARDEN, GERMANY, ASSIGNOR TO FRIED. KRUPP AKTIEN-
GESELLSCHAFT GERMANIAWERFT, OF KIEL-GAARDEN, GERMANY.

ELECTRIC HEATER.

No. 927,173.

Specification of Letters Patent.

Patented July 6, 1909.

Application filed May 20, 1908. Serial No. 433,924.

To all whom it may concern:

Be it known that I, KARL SCHLÜTER, a subject of the Emperor of Germany, and a resident of Kiel-Gaarden, in the Empire of Germany, have invented certain new and useful Improvements in Electric Heaters, of which the following is a specification.

The subject of the present invention is an electric heater, having its resistance members constructed of nickel tubes. Heaters with such resistance members possess especial efficiency because the material of the resistance possesses a high electrical temperature coefficient, a high specific resistance, and a high heat radiating coefficient, and, because the form in which it is possible to embody the metal, in producing the resistance, causes the surrounding air to contact with the greatest possible superficial area, thereby preventing over-heating of the resistance.

One embodiment of the invention is shown by way of example in the accompanying drawings, in which—

Figure 1 shows the heater in longitudinal section, and Fig. 2 shows the heater in cross-section.

In a housing A, a comparatively large number of thin walled nickel tubes B are mounted through insulation in transverse sheet metal walls C, so as to constitute a condenser type of structure. In the walls C and between the tubes B are provided a large number of bores c'. The nickel tubes B, through the medium of suitably disposed sheet metal strips D, are interposed in series in an uninterrupted conductor for electrical current. The ends of this conductor terminate in two binding posts E mounted through insulation upon the housing A. In the end walls of the housing A are located an air intake F and an air outlet G. The former stands in communication with the atmosphere, while the latter leads to the place of use of the warmed air, as for example, the combustion chamber of an internal combustion engine.

If the binding posts are suitably connected to a source of electricity, electric current flows through the circuit provided by the

group of tubes B and the metal strips D and 50 is converted into heat by the resistance of the nickel tubes. The heat thus produced is given off to the air within and surrounding the tubes B. If air is forced through the pipes F and G, in the direction of the arrows 55 x, y, the air flows partly through the tubes B and partly through the opening c' of the walls C which communicates with the space surrounding the group of tubes, and would become highly heated in consequence of the 60 great contact surface provided by the resistances B.

Experiments have shown that a heater constructed in the described manner will stand a current of thirty amperes per square 65 millimeter of conductor section and at the same time, is self-protected against over-heating, by the high electrical temperature coefficient of the nickel. The heater is also shown by experiments to withstand temperature fluctuations of 900 degrees centigrade and over with swift air currents, without danger of fracturing the nickel tubes. Furthermore, since nickel tubes are only slightly oxidized at very high temperatures, 75 the heater possesses a great lasting quality.

Having thus described the invention, what is claimed and desired to be secured by Letters Patent is:—

In an electric heater, the combination 80 with a housing open at the top and provided in one end-wall with an air-intake and in the other end-wall with an air-outlet; of a top-plate adapted to close said housing; tubular resistance members of nickel open at both 85 ends and suspended from said top-plate with the open ends of said tubes adjacent to the intake and outlet respectively; means for insulating said tubes each from each and from said top-plate; and connections whereby said 90 tubes are joined separately in series.

The foregoing specification signed at Kiel, Germany, this 5th day of May, 1908.

KARL SCHLÜTER.
